T. S. Lambert.

UNITED STATES PATENT OFFICE.

T. S. LAMBERT, OF PEEKSKILL, NEW YORK.

IMPROVED DOUBLE WINDOW.

Specification forming part of Letters Patent No. 47,837, dated May 23, 1865.

To all whom it may concern:

Be it known that I, T. S. LAMBERT, of Peekskill, Westchester county, New York State, have invented a new and useful Improvement in Double Windows; and I do hereby declare that the following is a full and exact description thereof, reference being had to the accompanying drawings, and to the letters of reference marked thereon.

The nature of my invention consists in providing an inside double window composed of an upper and lower sash, sliding in the stops of the outer window, made to press against the sash by a strip of paper, cloth, rubber, or other material, that holds the sash in place, therefore, and obstructs the passage of air, serving also to sustain the sashes when raised or lowered, the front of the stop being also furnished with a molding or strip, applied so as to cover the material behind the stop. The whole has a finished appearance, and is a lighter, neater, more perfect, and cheaper sliding double window than any heretofore invented.

To enable others skilled in the art to make and use my invention, I will describe its construction and operation.

Figure 1 represents an inside view of the double window, the upper sash lowered and the lower one raised. Fig. 2 represents a section of the inner and outer window and the frame at one side, indicated by the dotted black line, Fig. 1.

The same letters indicate in each figure corresponding parts.

A represents in Fig. 1 the inner edge of the frame of a window to which the inner casing of it is attached, and against which the stop F, Fig. 2, is placed unless separated by K, (shown by the dotted red line in Fig. 1, and by red also in Fig. 2,) which material (represented by K) is interplaced between the frame and stop to obstruct the passage of air and to cause pressure against the sashes G and H.

x and y, Fig. 2, represent grooves in the stop F, fitted, as may be readily seen, by corresponding tongues of the sashes G and H.

I represents a strip or thin molding applied to the front edge of the stop F. In Fig. 2 it may be seen overlapping the front edge of the frame A, and also the inner surface of the sash H, thus covering the joint of the sash with the stop and hiding the material K and covering

its joints with the frame on the one hand and the stop on the other.

E represents the lower sash of the outer window.

D represents a stop under the upper outer sash.

C represents the outer stop of upper sash, and B represents the outer casing of the frame.

L L' represent the upper and lower stops, reaching over and under the inner sashes back to the outer sash.

The material represented by K may be merely interplaced, but it is more convenient to have it fastened to the frame. The stops then being applied to each side of the sashes, they may be pressed into their proper position, and will be held usually without any further fastening; or a single screw may be inserted through each stop about midway of the lower sash. When spring comes and the double windows are removed, the stops may be replaced, or, what will appear better, they can be inserted or exchanged from side to side, and thus the grooved surfaces turned in and the smooth side out. Thus but one set of stops will be required for summer and winter use. The stops may be deeper than the frame without objection, as the molding I will hide the otherwise defect, or if the stops do not extend to the front edge of the frame A the molding I can be made to abut against the frame A.

The sashes for such an inner window may be with propriety made of three-fourths of an inch thick lumber, or even five-eighths stuff will answer. The sash will therefore be light, easily held by the action of the material K, without weights, springs, or other fastenings.

What I claim as my invention, and desire to secure by Letters Patent, is—

1. The combination of the convertible stop F and its molding I and the sashes G and H, with the frame A, in the manner and for the purpose substantially as set forth.

2. The combination of the material K with the stop F, the molding I, the sashes G and H, and the frame A, in the manner and for the purpose substantially as set forth.

T. S. LAMBERT.
